C. F. FREDE.
CHARGING CAR FRAME,
APPLICATION FILED APR. 9, 1915.

1,165,959.

Patented Dec. 28, 1915.

Inventor
Charles F. Frede
By *H. C. Grinnell, Atty.*

UNITED STATES PATENT OFFICE.

CHARLES F. FREDE, OF ST. LOUIS, MISSOURI, ASSIGNOR TO COMMONWEALTH STEEL COMPANY, OF ST. LOUIS, MISSOURI, A CORPORATION OF NEW JERSEY.

CHARGING-CAR FRAME.

1,165,959.

Specification of Letters Patent. Patented Dec. 28, 1915.

Application filed April 9, 1915. Serial No. 20,222.

To all whom it may concern:

Be it known that I, CHARLES F. FREDE, a citizen of the United States, residing at St. Louis, Missouri, have invented a certain new and useful Improvement in Charging Car Frames, of which the following is a full, clear, and exact description, such as will enable others skilled in the art to which it appertains to make and use the same, reference being had to the accompanying drawings, forming part of this specification, in which—

My invention relates generally to railway car frames, and more particularly to the frame of a charging car, *i. e.*, a car utilized for transporting charging boxes.

The principal objects of my invention are to generally simplify and lessen the cost of construction of charging car frames, and to make the same strong and rigid, and to accomplish these objects, I propose to make the entire frame in a single piece, preferably by casting, and to form integral with said frame essential parts, such as the upper portions of the journal boxes, the draft gear lugs, and upwardly projecting frames at each end, which latter prevent displacement of the charging boxes while the cars are being hauled or coupled together.

With the foregoing and other objects in view, my invention consists in certain novel features of construction and arrangement of parts, hereinafter more fully described or pointed out in the claims, and illustrated in the accompanying drawings, in which—

Figure 1 is a top plan view of a charging car frame of my improved construction. Fig. 2 is a side elevational view of the car frame. Fig. 3 is an enlarged cross sectional view taken approximately on line 3—3, of Fig. 1. Fig. 4 is an enlarged end elevational view of the car frame.

Referring by numerals to the accompanying drawings, 1 designates the side sills of the frame, 2 the center sills, 3 the end sills, 4 the body bolsters or transoms. These parts are integrally formed preferably by casting, and said parts may be of any desired cross-sectional shape.

As shown the side sills 1 and center sills 2 are channel shape in cross-section with their flanges outwardly presented, and the transoms or bolsters 4 are of I-beam shape in cross-section.

Formed integral with the end sills 3, are upwardly projecting brackets 5, which are for the purpose of preventing endwise displacement of the charging boxes while the cars are being hauled, or while they are being coupled to each other.

Formed through the center portions of the end sills 3 are openings 6, which accommodate the coupler draw-bars.

Formed integral with or fixed to the inner face of the center sills 2 between the end sills 3 and bolsters 4 are pairs of draft gear lugs 7, the lower portions of which are united by horizontally disposed plates 8.

Removably positioned on top of the lugs are plates 9 and the spaces between the pairs of plates form pockets for the follower blocks associated with the draft rigging, which may be utilized on the frame.

Formed integral with the lower portions of the side sills 1, and at the ends of the bolsters or transoms 4 are horizontally disposed plates 10 which constitute the upper portions of journal boxes. These plates are preferably perforated in order to receive bolts or the like, which are utilized in attaching the lower portions of the journal boxes.

In Fig. 2 I have shown in dotted lines a series of charging boxes positioned on the frame.

By my improved construction, a charging car frame can be easily and cheaply produced, and as said frame is cast in a single piece, it is very strong and rigid and able to withstand to a maximum degree, the rough usage to which it is subjected in service.

It will be readily understood that minor changes in the size, form and construction of the various parts of my improved charging car frame can be made and substituted for those herein shown and described without departing from the spirit of my invention, the scope of which is set forth in the appended claims.

I claim:

1. As a new article of manufacture, a charging car frame formed in a single piece, and comprising side sills, center sills, end sills, transoms, and journal box parts on said side sills.

2. As a new article of manufacture, an integrally formed frame for charging cars

comprising side sills, journal box parts thereon, end sills and charging box retaining brackets on said end sills.

3. As a new article of manufacture, an integrally formed frame for charging cars comprising side sills, journal box parts formed thereon, center sills, end sills, and charging box retaining brackets on said end sills.

10 4. As a new article of manufacture, an integrally formed frame for charging cars comprising side sills, journal box parts formed thereon, transoms, end sills, and charging box retaining brackets on said end sills.

15 5. As a new article of manufacture, an integrally formed frame for charging cars, journal box parts integral with said frame, and charging box retaining brackets integral 20 with and projecting upwardly from the end portions of said frame.

6. As a new article of manufacture, an integrally formed frame for charging cars

comprising side sills, journal box members integral therewith, center sills, draft gear 25 lugs integral therewith, end sills, charging box retaining brackets projecting upwardly therefrom, and transoms.

7. As a new article of manufacture, a charging car frame having side sills, and 30 journal bearing plates formed integral with said side sills.

8. As a new article of manufacture, an integrally formed charging car frame comprising side sills, journal bearing plates integral with the lower portions of said side sills, center sills having draft lugs, and end sills provided with upwardly projecting charging box retaining brackets.

In testimony whereof I hereunto affix my 40 signature in the presence of two witnesses, this 3rd day of April, 1915.

CHARLES F. FREDE.

Witnesses:
